UNITED STATES PATENT OFFICE.

CHARLES W. SPERNADER, OF OAK PARK, ILLINOIS.

RAILWAY BLOCK SYSTEM.

974,716.

Specification of Letters Patent.

Patented Nov. 1, 1910.

Application filed May 26, 1909. Serial No. 496,024.

To all whom it may concern:

Be it known that I, CHARLES W. SPERNADER, a citizen of the United States, residing at Oak Park, in the county of Cook and State of Illinois, have invented certain new and useful Improvements in Railway Block Systems, of which the following is a specification.

This invention relates to safety appliances for railways, and has particular reference to devices employed in block signal systems whereby it is made impossible for one train to enter a block occupied by another train and whereby rear-end collisions will be avoided.

For a full understanding of the invention, reference is to be had to the accompanying drawings, in which,

Figure 1 is a diagrammatic representation of a block signal system, substantially in accordance with this invention; Fig. 2 is a similar view showing the same invention applied to a railway crossing; Fig. 3 represents a preferred embodiment of one of the movable contact devices hereinafter described; Fig. 4 is a detail of the shiftable shoe or slide associated with one of the rails. Fig. 5 is a vertical detail section on the line 5—5 of Fig. 1.

Throughout the following description and on the several figures of the drawings similar parts are referred to by like reference characters.

Referring to Fig. 1, the numeral 10 indicates a main line of a railway over which trains are presumed to be operated in the direction indicated by the arrow thereon. On said figure are represented two block stations A and B, and it is to be understood that any number of such stations may be employed and that the others would be equipped and arranged the same as those indicated. Said stations may be any desired distance apart. At each station there would be a device, such as indicated at 11 in the form of a bar associated with one of the track rails and normally projecting slightly above the top of the rail whereby a passing car wheel will cause the same to be depressed. When the shoe 11 is thus depressed a contact point 12 carried or operated thereby will be brought into contact with a contact point 13, closing a circuit from the main wire 14 through branch wires 15 and 16 to a solenoid 17, the circuit being completed through a ground wire 18. When

the solenoid 17 is energized the armature thereof will be drawn so as to cause a contact point 20 to engage a contact point 21 whereby a circuit will be completed from the main wire 14 through branch wires 22 and 23 to a solenoid 24, the circuit, for instance, being completed through a ground wire 25.

The solenoid 24 may be placed at any suitable point with respect to the shoe 11 and is adapted when energized to cause a stop-member 26 to be elevated into the path of a trip device carried preferably by the locomotive or car and to trip the air-brake mechanism thereof. The devices carried by the locomotive or car form no part of this invention and are not illustrated. As shown in this instance, the armature 24' of the solenoid 24 is connected to a lever 27 in such a manner as to cause the stop-member 26 to be elevated. It is to be understood, however, that the specific mechanical arrangement of devices to carry out the objects of this invention may be varied to a great extent within the scope of this invention and I do not desire to be limited except as may be necessitated by the state of the art.

The shoe 11 upon being engaged by the first wheel of a car or train will be depressed, causing the contact of the members 12 and 13, as already stated, and said shoe is long enough to insure that at least one wheel of the train or car will remain in engagement therewith until the last wheel has passed thereover. While the train or car is passing over the shoe 11, therefore, the circuit will be maintained through the solenoid 17 and solenoid 24. After the last wheel, however, has left the shoe, the contacts 12 and 13 will be separated by the restoration of the shoe to its normal position by any suitable means, such as a spring 28. The solenoid 17 will then be deenergized, but the circuit will be continued through the wires 22 and 23 and solenoid 24, maintaining the stop 26 in its elevated position so as to prevent a succeeding car or train from entering the block which has now been entered by the first train.

After the train has left station A and has reached station B, the shoe 11^b will be depressed in the manner similar to that already described in connection with the first station, causing the contact member 12^b to engage contact member 13^b, closing the circuit from the main line 14 through the

branch circuit 15^b and 16^b and the solenoid 17^b, whereby the armature 19^b will close the circuit through the contacts 20^b and 21^b and branch wires 22^b and 23^b and the solenoid 24^b, causing the stop 26^b to be lifted.

While the train is passing station B and the contacts 12^b and 13^b are held together, the circuit will be completed not only through the solenoid 17^b, as above described, but also an additional circuit will be completed from the main line 14 through the wire 15^b and wire 28 extending back to station A and whereby solenoid 29 will be energized, the circuit being completed through the ground wire 30. Upon the energization of the solenoid 29, the armature 19, common to both solenoids 17 and 29, will be shifted so as to cause the contact point 29 to engage a contact 31 and whereby the circuit will be completed through the wire 28 and wire 23, maintaining the energization of solenoid 24, and holding the stop 26 elevated until the train has passed station B. When the last wheel has left shoe 11^b of station B, the contacts 12^b and 13^b will break the circuit from the main line through the branch line 28 and whereby the solenoids 29 and 24 will be deenergized and the stop 26 will be permitted to drop. At this time the second train may enter the station or block A.

As described above, it being necessary for station B to be reached in order to adjust the devices at station A so that a succeeding train or car may pass thereover, it has been found necessary to devise means whereby in the event that the first train is not caused to pass station B, as, for instance, if it is desired to pass upon a switch located between the stations represented at C, for the trip device 26 to be freed. The movable switch point 32 either carries or operates a contact point 33 which, when the switch is open, will engage a contact point 34 to close the circuit from the main line through the branch wires 35 and 36, the latter being connected to a solenoid 37, connected to the armature 19, and having a function similar to that of solenoid 29. After the train has entered the switch and the switch closed, the contact points 33 and 34 will break the last mentioned circuit, with the same effect as above described in connection with the circuit 28 from station B, leaving the main line open and the devices at station A in such position as to permit the succeeding train to move thereover.

In Fig. 2 is indicated a similar arrange-

ment adapted to protect a railway crossing assuming that a train is passing the crossing on track D in the direction indicated by the arrow and it is desired to prevent a train on the track E from crossing said track. The first mentioned train will operate a shoe 11^c closing the contacts 12^c and 13^c whereby the circuit will be completed through the main line 14^c and branch wires 15^c and 16^c to the solenoid 17^c. The solenoid 17^c will cause the contacts 20^c and 21^c to complete the circuit from the main line 14^c through the branch wires 22^c and 23^c to the solenoid 24^c, causing the stop 26^c to be elevated to the position to stop the train on track E. A shoe 11^c suitably located on the opposite side of the track E is arranged in such a manner as to cause the contacts 12^c and 13^c to be engaged and complete the circuit from the main line through the branch wires 15^c and 28^c to the solenoid 29^c. A circuit will be completed through the same wires and contact points 20^c and 21^c maintaining the circuit through the solenoid 24^c while the train is passing over the shoe 11^c. After the train has passed shoe 11^c said shoe will be restored to its normal position breaking the circuit, whereby the solenoids 29^c and 24^c will be deenergized thereafter permitting the stop 26^c to drop.

Having thus described the invention, what is claimed as new is:—

In a safety appliance for railways, combination of a stop member, a solenoid to set the same, a pair of solenoids 17 and 29 with a common armature, a depressible shoe, means to energize solenoid 17 controlled by said shoe, means operative said armature to energize solenoid 24, means to restore the shoe and thereby to break the circuit through solenoid 17 after passage of a train, the circuit through solenoid 24 being continued, a second depressible shoe, means controlled by the said shoe to cause the second solenoid 24 to said pair to shift the common armature to reenergize solenoid 24, said last mentioned solenoid being momentarily deenergized during the shifting of said armature, means to restore the second shoe to break the circuit through solenoids 24 and 29.

In testimony whereof I affix my signature in presence of two witnesses.
